United States Patent Office

Des. 181,451
Patented Nov. 19, 1957

181,451

GAME BOARD

Joseph Barbieri, Springfield, Mass.

Application August 22, 1956, Serial No. 42,695

Term of patent 14 years

(Cl. D34—5)

E±0.1

正土四-2-

ANSWER

Fig. 1 is a top plan view of a game board showing my new design; and

Fig. 2 is a sectional view thereof taken on line 2—2 of Fig. 1.

Fig. 1. Parts of the drawing are lined for color.

I claim:

The ornamental design for a game board, as shown and described.
